UNITED STATES PATENT OFFICE.

BYERS W. KADEL, OF BALTIMORE, MARYLAND, ASSIGNOR TO THE T. H. SYMINGTON COMPANY, OF NEW YORK, N. Y., A CORPORATION OF DELAWARE.

COMPOSITE CAR FRAMING.

Application filed August 26, 1921. Serial No. 495,636.

To all whom it may concern:

Be it known that I, BYERS W. KADEL, a citizen of the United States, residing at Baltimore, in the State of Maryland, have 5 invented certain new and useful Improvements in Composite Car Framing; and I do hereby declare the following to be a full, clear, and exact description of the invention, such as will enable others skilled 10 in the art to which it appertains to make and use the same.

The invention relates to railway cars, and more particularly to plate members adapted to be used in the construction of gondola and cars of like character.

The principal object of my invention, broadly stated, is to provide plate-like members which may be produced by an inexpensive process and which are suitable for 20 use in constructing the side walls of gondola cars.

Another object of the invention is to provide plate members comprising expanded metal plates having solid marginal edges, 25 the expanded metal being covered by a composite filler whereby the metal is protected from the elements and rendered sufficiently rigid to afford efficient side walls for a car construction.

30 There are other objects of the invention as will hereinafter more fully appear from the detailed description of the single embodiment thereof which has been chosen to illustrate the invention.

35 In the drawings,—

Figure 1 is a fragmentary side elevation of a portion of a gondola car showing the invention applied thereto.

40 Figure 2 is a transverse sectional view showing the manner in which the plates are connected to the load carrying frame of the car.

Figure 3 is a perspective view of one of the plates.

45 The numeral 1 designates a railway car having the usual form of angle iron framework 2 to which in general practice is applied the sheet metal siding in order to complete the side walls of the car. The 50 numeral 3 designates a plate embodying my invention. The plate is preferably formed from relatively thin metal having the interior portion 4 thereof expanded or perforated as is common in expanded metal.

The marginal edges 5 of the plates are 55 preferably reinforced by overlapping two thicknesses of the plate, as clearly shown at 6 in Fig. 2. These marginal edges are punched as at 7 to provide rivet receiving openings for the reception of rivets 7^a by 60 which the plates are attached to the car framework 2. The intermediate or expanded metal portion of the plate is coated or covered with a composite filler 8. This composite filler may comprise concrete. It 65 is, however, preferably formed of a mixture of cellulose, cement and plaster of Paris. Such a compound is inexpensive, simple to apply and has the requisite strength and 70 rigidity, and forms a surface which is practically impervious to the action of acids. The surface is also of sufficient hardness to prevent rapid wear by the lading of the car. It will be understood, however, that 75 while I have particularly described one plastic compound, I do not limit myself thereto, since many other compounds may be advantageously applied or used in combination with the expanded metal plate.

I claim:—

1. In a railway car, the combination with a metallic load carrying frame, of wall members, said wall members including a plurality of plate like elements each of which comprises a single metallic frame section 85 and a composite filler, said composite filler terminating short of the surrounding marginal edges of said metallic frame section.

2. In a railway car, the combination with a metallic load carrying frame, of plate members secured thereto, said members comprising plates of expanded metal having applied thereto in spaced relation to the marginal edges thereof a composite filler. 90

3. In a railway car, the combination with a load carrying frame, of wall members therefor, said wall members comprising a plurality of plates having their adjacent edges overlapped, the central portions only of said plates having applied thereto a composite filler. 95

4. In a railway car, the combination with a load carrying frame, of wall members therefor, said members comprising a plurality of overlapping plates, the central portions of which are formed from expanded metal covered with a composite filler, the marginal edges of said plates be- 100 105 108

ing perforated, and fastening means extending through the perforations in two adjacent plates.

5. An article of manufacture comprising a plate, the central portion of which is formed of expanded metal covered with a composite filler, the margins of said plate being integrally connected to said central portion and being provided with openings 10 adapted to receive means for securing said plate to a support.

6. An article of manufacture comprising an integral metal plate having its central portion formed of expanded metal, a composite filler covering said central portion, the marginal edges of said plate being bent

upon themselves and provided with rivet receiving openings.

7. In a railway car, the combination with a load supporting frame including spaced 20 uprights, of a plurality of plates connected to said frame with their edges overlapping adjacent uprights, said plates constituting load retaining walls, each of said plates comprising an integral metal plate having 25 its central portion formed of expanded metal, means for reinforcing the edges of said plates, and means passing through said edges for connecting the plates to the car frame.

In testimony whereof I affix my signature.

BYERS W. KADEL.
